UNITED STATES PATENT OFFICE

FRED W. OTT, OF NEW HAVEN, CONNECTICUT

POWER MECHANISM

Application filed May 18, 1923. Serial No. 278,772.

This invention relates to new and improved power mechanism and it is the object thereof, among other things, to produce mechanism of this character that may provide the maximum power pressure with the minimum manual effort.

To these and other ends, my invention consists in the power mechanism, having certain details of construction and combinations of parts, as will be hereinafter described and more particularly pointed out in the claims.

Referring to the drawings, in which like numerals of reference indicate like parts in the several figures;

Figure 1 is a transverse sectional view of my improved power mechanism, the parts in section being taken generally upon line 1—1

of Figure 3;

Figure 2 is a fragmentary elevation, the parts in section being taken generally upon line 2—2 of Figure 3;

Figure 3 is a plan view thereof, with a portion of the outer element broken away;

Figure 4 is a transverse sectional view upon line 4—4 of Figure 1; and

Figure 5 is an enlarged detail view showing particularly the operating lever and adjacent mechanism, the parts in section being taken generally upon line 5—5 of Figure 3.

In the embodiment of my invention as herein disclosed, 10 is the body member which is substantially rectangular in cross section that is closed at its ends by cover plates 11, each of which is provided with a radial slot 12. Projecting through the body member 10 and cover plate 11 are the rods 13, which also extend through the cam slots 14 in the cam plates 15.

For the purpose of minimizing friction, each rod 13 near its outer end is encircled by a roll 16, which rides in the slot 12, a roll 17, which rides within a cam slot 14, and a spacing collar 18 therebetween.

Fixed to the inner face of each cam plate 15 or integral therewith, as desired, is a pinion 19, the teeth of which mesh into similar pinions 20 fixed on the shafts 21 that are journaled in the cover plates 11.

Mounted in one of the cover plates 11 is a stub shaft 22, having a pinion 23 thereon, the

teeth of which mesh into the teeth of the rack 24 on one of the cam plates 15. This shaft 22 is rotated through a manually operated lever 25, which preferably has a ratchet connection therewith. The details of this ratchet connection are not shown, because it is of standard construction. On this shaft is a ratchet 26 which co-operates with a pawl 27 to prevent premature rotation of the shaft. Manipulation of the lever 25 rotates the upper cam plate 15, and by reason of the cam slots 14 the rods 13 are moved toward and away from each other. The movement of the upper cam plate is transmitted to the lower cam plate through the pinions 19, 20, 28 and 29.

The engagement of the rods 13 with the slots 12 maintain their relative alignment with each other.

The cover plates 11 and the above mechanism outside of the outer faces thereof are enclosed within a cap 30 that is fixed to the plates 11, substantially as shown, or in any other convenient manner.

Movably mounted within the body member 10 and through the upper cap and adjacent parts is a plunger 31 having a contact plate 32 at its upper end and terminating at its lower end in a guide block 33, having laterally projecting lugs 34 which travel in grooves 35 in the inner walls of the body member 10.

Between the guide block 33 and the upper of the cover plates 11, are a plurality of cam members 36, each of which is provided with a plurality of cam faces 37 in the form of inclined planes which terminate in stop shoulders 38. In these cam members are journaled the rolls 39, which contact with and are upon opposite sides of the rods 13, as shown in Figure 4.

Between each cam face 37 and the adjacent cam face is a roll 40, the outer ends 41 of which project into the grooves 35 and prevent displacement thereof. All of these cam members 36 are provided with cam faces upon opposite sides thereof, except the one at the top and the one at the bottom, both of which have cam faces upon one side only and a straight face upon the opposite side. The upper cam member is in contact with rolls 42 journaled in the cover plate 11 and the lower cam mem-

ber with rolls 43 journaled in the guide block 33.

The movement of the rods 13 toward each other cause the rolls 40 to ride to the low point of each of the cam faces 37, and thus positively move the plunger 31 inwardly so that the contact plate 32 will be brought closer to the cap 30 and the reverse result obtains during the movement of the rods 13 away from each other.

Between the guide block 33 and the lower cover plate 11, are a plurality of cam members 44 that are substantially the same design and structure as the cam members 36, except that the direction of inclination of the cam faces 45 is the reverse of those of the cam faces 37, so that as the rods move toward each other, the rolls 40 move toward the lower part of the cam faces 45. Hence the plunger 31 is positively moved in both directions, in one direction the pressure being applied from the cam member 36 upon one side of the guide block 33, and in the other direction by the cam member 36 on the opposite side of the block 33.

The upper and lower cam members 44 are provided with one straight face against which ride the rolls 46 connected with the block 33 and rolls 47 connected with the lower cam plate 11.

By this mechanism, very limited manual power applied to the lever 25 is magnified into a very powerful action of the plunger 31, which is taken advantage of when the device is either used as a jack or for other purposes through the contact plate 32.

There are minor changes and alterations that may be made within my invention and I would therefore have it understood that I do not limit myself to the exact construction herein shown and described, but claim all that falls fairly within the spirit and scope of the appended claims.

Having described my invention, what I claim as new and desire to secure by Letters Patent, is:—

1. In mechanism of the character described; a body member; a plunger; a guide block connected with the plunger; a plurality of cam members, some of the cam members being upon one side of the guide block and other of the cam members being upon the opposite side thereof; a plurality of rolls between the cam faces of the cam members; and means for moving the cam members toward and away from each other whereby reciprocatory movement is imparted to the plunger, the cam faces upon the cam members upon one side of the guide block being inclined in a direction opposite to those upon the other side of the guide block.

2. In combination with a body and a reciprocal plunger, having an abutment, rods on opposite sides of the plunger, cam members connected to the rods and disposed on

opposite sides of the abutment for moving the latter and thereby the plunger in opposite directions, the cam faces of the cam members on one side of the abutment being inclined oppositely to the cam faces on the other side thereof, means to move the rods toward and away from one another, and means between adjacent cam members guidingly supported by the body for causing the cam members to act against the abutment.

3. In combination with a reciprocal plunger having a block thereon, a pair of rods disposed parallel to the plunger and bodily movable radially thereof, rotary members having cam slots receiving the rods therein for effecting said radial movement of the rods, two sets of cam members on each side of the block, the cam faces of the cam members on one side of the block being reversely inclined with respect to those on the opposite side of the block, means for the cam members of the sets to cause same to act on the block, and means to effect movement of the rotary members.

4. In combination with a reciprocal plunger having a block thereon, a pair of rods disposed parallel to the plunger and bodily movable radially thereof, rotary members having cam slots receiving the rods therein for effecting said radial movement of the rods, two sets of cam members on each side of the block, the cam faces of the cam members on one side of the block being reversely inclined with respect to those on the opposite side of the block, means for the cam members of the sets to cause same to act on the block, and means to effect movement of the rotary members, including a curved rack on one of the rotary members, and a rotatable pinion engaged with the rack.

In testimony whereof, I have hereunto affixed my signature.

FRED W. OTT.
